UNITED STATES PATENT OFFICE

FORREST H. GILMORE AND HERMAN H. KRUGER, OF SAN PIERRE, INDIANA

ANTICREEPING DEVICE

Application filed May 16, 1931, Serial No. 537,918. Renewed August 16, 1932.

This invention relates broadly to railways, and has more particular reference to devices utilized to prevent spreading of the rails.

It is therefore a primary object of this invention to provide an improved device for securely anchoring the rails, and to prevent spreading of the rails.

A still further object of the invention is to provide a device of the character above mentioned, which serves to connect two parallel rails to prevent the rails from spreading or being displaced laterally relative to one another.

Other objects and advantages of the invention, and the nature of the invention will be best understood from a study of the following description and accompanying drawings wherein we have shown what is intended as a preferred embodiment of the invention, although it is to be understood, at the outset, that the invention is susceptible to further changes, modifications and improvements coming within the scope of the appended claims.

In the drawings:

Figure 1 is a top plan view showing the application of the device.

Figure 2 is a fragmentary elevational view for more clearly illustrating the invention.

Figure 3 is a sectional view taken substantially on the line 3—3 of Figure 2.

Figure 4 is an edge elevational view of a tie plate.

Figure 5 is a top plan view thereof.

Figure 6 is a top plan view of a gauge rod.

Figure 7 is a bottom plan view of a hood plate.

Figure 8 is an edge elevational view of the hood plate.

Figure 9 is an edge elevational view of one end portion of the gauge rod.

Referring more in detail to the drawings, 1 and 2 designate the rails of a railway and 3 designates the usual tie.

In carrying out our invention, we provide for each rail, a tie plate 5 that is suitably supported on the cross tie 3. On the top face of the tie plate 5 is provided a transverse groove 6 within which is disposed the base flange of the rail, and the groove 6 is prefer-

ably of a width greater than the width of the rail base flange. Thus is provided adjacent one end of the tie plate 5 a raised or shoulder portion 7 provided on its inner edge with a groove 8 within which is received one edge 55 of the rail base flange.

The tie plate 5 at that end thereof remote from the shoulder portion 7 and inwardly from its longitudinal edges, is provided with a longitudinal groove 9 for accommodating 60 an end portion of a relatively narrow elongated gauge rod 10 that extends between the rails 1 and 2 and which at each end thereof is provided with a cross head 11 adapted to fit within the groove 6 of a tie plate parallel 65 to the rail. Each of the cross heads 11 at its free longitudinal edge is reduced in thickness to provide a longitudinally extending lip 12 adapted to overlie the adjacent edge portion of the rail base flange. 70

For each tie plate 5, there is provided a substantially channel shaped hood plate 13 that is engageable with the tie plate at that end of the plate remote from the shoulder 7 and which has the opposite side portions 75 thereof provided with internal grooves 14 for slidably accommodating laterally projecting ribs 15 provided at opposite longitudinal edges of the tie plate 5.

It will be thus seen, and as is illustrated 80 in Figure 3, that the top of the hood 13 closes the top of the groove 9 and serves to maintain an end of the gauge rod 10 within the groove 9.

The opposite side portions of each hood 13 85 at one end of the hood are provided with notches 16 for engaging an adjacent edge portion of the base flange of an adjacent rail.

Each of the tie plates 5 are anchored in position on the tie 3 through the medium of spikes or like fastening elements 17 driven into the tie 3, and through holes provided in the shoulder 7 adjacent the grooved edge of the shoulder. Additional spikes or similar fastening elements 18 are also employed, and these spikes pass through holes provided in the top of the hood 13, and through holes provided in the adjacent cross head 11 which holes also register with holes provided for the spikes 18 in the plate 5, and suitably lo- 95 100

cated to aline with the holes in the cross head 11.

In actual practice then it will be apparent that the rails will be secured in position with- 5 in the grooves 6 of the tie plates 5, and the shoulders 7 of the tie plates will prevent spreading of the rails away from one another, while the gauge bar 10 with the heads 11 en- 10 gaging the base flanges of the rail will pre- vent the rails from moving inwardly toward one another. Thus the rails will be held in true parallelism, and will be prevented from creeping.

Having thus described our invention, what 15 we wish to claim as new is:

1. A tie plate provided with a transverse groove and a longitudinal groove intersecting the transverse groove, said plate adapted to receive in the transverse groove thereof the 20 base flange of a rail, a gauge rod having an end portion received in the longitudinal groove and provided with a cross head located in the transverse groove and engaging an adjacent edge portion of the base flange 25 of the rail for retaining said base flange within said transverse groove, and a hood plate engaging the tie plate and bridging the longitudinal groove, said hood plate serving to retain said end of the gauge rod within said 30 longitudinal groove.

2. A tie plate provided with a transverse groove and a longitudinal groove intersecting the transverse groove, said plate adapted to receive in the transverse groove thereof the 35 base flange of a rail, a gauge rod having an end portion received in the longitudinal groove and provided with a cross head located in the transverse groove and engaging an adjacent edge portion of the base flange of 40 the rail for retaining said base flange within said transverse groove, and a hood plate engaging the tie plate and bridging the longitudinal groove, said hood plate serving to retain said end of the gauge rod within said 45 longitudinal groove, said hood plate and said tie plate provided with cooperating means for slidably retaining the hood plate on the tie plate.

3. In combination with a pair of opposed 50 rails, a tie plate supporting each of said rails and provided with a transverse shoulder en- gaging the base flange of an adjacent rail at the outer side of the rail, a gauge plate ex- 55 tending between the rails, said gauge rod at each end thereof provided with a cross head en- gaging the base flange of an adjacent rail on the inner side of the rail and cooperating with the shoulders of said tie plate for re- 60 taining the rails against lateral displacement relative to one another.

4. In combination with a pair of opposed 65 rails, a tie plate supporting each of said rails and provided with a transverse shoulder en- gaging the base flange of an adjacent rail at the outer side of the rail, a gauge plate ex-

tending between the rails, said gauge rod at each end thereof provided with a cross head 70 engaging the base flange of an adjacent rail on the inner side of the rail and cooperating with the shoulders of the tie plate for clamp- 75 ing the rail therebetween, and a hood member embracing each of said tie plates on the inner side of the rail and engaging an adjacent end of the gauge rod for retaining said end in en- gagement with an adjacent rail.

5. In an anti-creeping device for railway rails, a tie plate provided with a shoulder for engag- 80 ing the rail at one side thereof, a member on the tie plate and constrained to slide longitudinally of the tie plate at right angles to the rail and engageable with the rail for clamping the rail between it and said shoulder and means slidably engaging the tie plate and having engagement with said longitudinally slidable member for retaining 85 the latter against perpendicular displacement relative to the tie plate.

6. An anti-creeping device for railway rails including in combination a tie plate provided with a shoulder for engaging one side of the 90 rail, and a channel member slidably embrac- 95 ing the tie plate and provided at relatively op- posite sides thereof for engaging the rail for clamping it between said shoulder and chan- nel member.

In testimony whereof we affix our signa- 100 tures.
